UNITED STATES PATENT OFFICE.

VICTOR M. SUMMA, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

CAR-UNDERFRAME.

1,080,178.

Specification of Letters Patent.

Patented Dec. 2, 1913.

Application filed November 24, 1911. Serial No. 662,148.

To all whom it may concern:

Be it known that I, VICTOR M. SUMMA, a citizen of the United States, residing at St. Louis, Missouri, have invented a certain new and useful Improvement in Car-Underframes, of which the following is a full, clear, and exact description, such as will enable others skilled in the art to which it appertains to make and use the same, reference being had to the accompanying drawings, forming part of this specification, in which—

Figure 1 is a side elevation of a portion of a car body and showing a half of my improved underframe. Fig. 2 is a horizontal section taken approximately on line 2—2 of Fig. 1 with parts of the underframe shown in horizontal section. Fig. 3 is an enlarged transverse section taken approximately on line 3—3 of Fig. 2. Fig. 4 is an enlarged transverse section taken approximately on the line 4—4 of Fig. 2. Fig. 5 is an enlarged transverse section taken approximately on the line 5—5 of Fig. 2. Fig. 6 is an enlarged detailed section taken approximately on the line 6—6 of Fig. 2.

This invention relates to an underframe construction particularly intended for use in connection with metallic cars, commonly termed steel cars, and the principal object of my invention is to generally improve the construction of steel car underframes and to provide a simple, inexpensive underframe which can be readily built from ordinary commercial shapes and plates and which underframe carries the entire load of the car body and its contents and thus as the car body is relieved of practically all load strains, said body or superstructure can be formed of comparatively light weight material.

My improved underframe is constructed entirely of metal and comprises a pair of side sills, a center sill, a pair of body bolsters, end sills, and a pair of intermediate transoms or cross bearers, all of which are particularly designed and arranged so as to utilize to the fullest extent the strength of the metal of which the various parts are formed and to construct and locate the various sills so as to effectually withstand such end shocks and service strains as they may receive in ordinary usage.

With the above objects in view, my invention consists in certain novel features of

construction and arrangement of parts hereinafter more fully described and claimed.

In the construction of my improved underframe, I make use of a pair of side sills, each comprising a vertically disposed plate 10 which extends the entire length of the car body and this plate gradually narrows in width toward its ends in order to form a sill having its greatest depth at center.

Riveted to the inner face of the plates 10 and extending continuously from end to end along the lower edges of said plates are angles 11, which practically form the lower chords of the side sills and applied to the central portions of the horizontal legs of 70 these angles are reinforcing plates 12. These plates materially strengthen the deep central portions of the side sills, which portions are naturally subjected to the greatest load strains.

Riveted to the outer faces of the plates 10, and extending along the upper edges thereof from one bolster to the other, are flat metal plates 13, which practically form top chords for the side sills.

The ends of the side sills are connected in any suitable manner to metallic end sills 14, and located at the corners of the frame thus formed are push pole pocket casings 15.

The body bolsters forming a part of my 85 improved underframe are arranged at suitable distances from the end sills 14 and each bolster comprises a pair of transversely disposed members 16, preferably web plates, which are continuous from one side sill to the 90 other, and said plates having their upper and lower edges bent into horizontal planes to form flanges 17 to which the top and bottom plates of the bolster are connected. The ends of these plates 16 are bent laterally to form flanges 18 and which latter are riveted directly to the plates 10 and angles 11 of the side sills.

While I have shown and described the transverse members 16, as being formed of 100 web plates, it will be readily understood that these members can be in the form of channels, I-beams, or of any other suitable shape.

19 designates the bottom plate of the body 105 bolster which is in the form of a flat plate, widest at its center and tapering in width toward its ends and said bottom plate is riveted directly to the flanges on the lower edges of the members 16. The ends of this 110

bottom plate preferably terminate a short distance from the angles 11 at the bottoms of the side sills.

A center bearing 19^a of any suitable construction is applied to the under sides of the central portion of the plate 19, and suitable side bearings 19^b are positioned on the under side of said plate adjacent its ends.

Vertically disposed members 20, preferably in the form of channels or plates, having flanges on their edges, are located between the members 16 and extend from the bottom plate 19 upwardly to the top plate of said bolster and the flanges on the sides of these members are riveted directly to the plates 16. The edges of the metal plates utilized as floor sheets 21, hereinafter more fully described, are applied to the flanges along the upper edges of the members 16, and over-lying these edges of the floor sheets is a transversely disposed plate 22 which forms the top plate of the bolster and the side edges of this top plate are rigidly fixed to the corresponding edges of the floor sheets 25 and the top flanges of the members 16 by means of rivets or in any suitable manner.

23 designates a pair of longitudinally disposed members, preferably in the form of channels, which extend from the central portion of the bolster to the end sill 14 and these members serve as draft sills for the underframe. The end portions of these sills are fixed to the front member 16 of the bolster and to the end sill 14 by means of angle brackets 24. Extending from the points where these draft sills unite with the bolster to the points where the end sill unites with the side sills, are diagonally disposed members 25 preferably in the form of channels, the ends of which are fixed in any suitable manner to the corresponding parts of the underframe, and these members serve as struts or braces to transmit the strains imposed on the ends of the end sill to the adjacent bolster.

Applied to each end sill, immediately in front of the draft sills 23, is a draw bar carry iron 26 of any desired construction.

The center sill of my improved underframe comprises a vertically disposed web plate 27 which extends continuously from one bolster to the other and the central portion of this web plate is considerably deeper than the end portions thereof, thereby forming a center sill of the well known fish belly type. Riveted to the lower edge of this plate 27 and extending from one bolster to the other, are angle members 28 which practically form the lower chord of the center sill. The ends of these angles 28 are riveted to the bottom plates 19 of the bolsters and the ends of the web plates 27 are connected to the inner ones of the members 16 by angle brackets 29.

Cross bearers are located between the end 65 portions of the deep central portion of the center sill and the corresponding portions of the side sills and each of these cross bearers comprises a pair of vertically disposed web plates 30, the inner ends of which bear directly against the web plate 27 and the outer ends of which bear against the plates 10 of the side sills. A pair of angle bars 31 are riveted to the upper edge of each plate 30 and a corresponding pair of angle bars 32 are 75 riveted to the lower edge of each plate. The inner ends of these cross bearers rest directly upon the angle bars 28 and said inner ends are fixed to the plate 27 in any suitable manner, preferably by means of angle brackets 80 33. The outer ends of the cross bearers rest upon the angle bars 11 and are fixed in any suitable manner to the lower portions of the side sills. Positioned on the under side of the cross bearer and riveted to the horizontally disposed flanges of the angles 32 are 85 reinforcing strips 34.

Horizontally disposed members 35, either angles or channels, extend between the top portions of the center sill 27 and side sills, 90 said members forming supports for the floor sheets 21, and the inner ends of said members are connected to the plate 27, preferably by means of angle brackets 36. The outer ends of these members 35 are connected to 95 the side sills in any suitable manner, either by means of angle brackets or by being riveted to the lower portions of the car body side posts.

Vertically disposed struts 35^a are arranged 100 between the central portions of the cross bearers and the members 35 which lie immediately above said cross bearers.

The outer edges of the floor sheets 21 are bent downwardly over the upper edges of 105 the plates 10 and over the plates 13 of the side sills, and said downwardly bent edges are fixed to these parts by means of rivets, or in any suitable manner. The inner edges of the floor sheets are flanged downwardly 110 and are connected by means of rivets, or in any suitable manner, to the upper edge of the center sill plate 27.

A cover plate 37 in the form of a long, narrow strip is positioned immediately over 115 the inner edges of the floor sheets 21 and these parts are connected by means of rivets or the like.

The side posts of the superstructure are preferably in the form of Z-bars 38, the 120 lower ends of which extend downward immediately inside of the plates 10, with their lower ends resting upon the horizontal flanges of the angles 11 and the lower portions of these side posts are fixed in any suitable manner to the plates 10.

The outer plates or sheets of the car wall are fixed to the side posts and the lower

edges of these plates or sheets extend downward over the downwardly bent side edges of the floor sheets 21.

Threshold plates 39, substantially angle-shaped, in cross section, are positioned in the door openings in the side wall of the car immediately over the corresponding portions of the floor sheets 21.

It will be noted that in my improved construction the downwardly bent edges of the floor sheets 21 form reinforcing members for the upper portions of the plates 10 and 27 and the body portions of said floor sheets practically form continuous lateral extensions of the top chords of the center and side sills, and which construction is very strong and rigid and provides an underframe of great load-carrying capacity. These several members, to wit, floor plates 21, sill plates 20 10, angles 11, and the side plates are standard, and therefore, of uniform weight in all cars. When cars of added length, or of increased capacity are desired, it is necessary that the chords of the supporting sills be increased in area according to the length or capacity of the car. The use of reinforcing members 12 and 13 permits this being done, as the weight of these reinforcing members may be varied to suit the particular instance, 25 and to maintain the uniform area of the upper and lower chords. Therefore, while the other members are uniform or constant, the reinforcing members 12 and 13 are variable members, and this construction permits 30 of considerable latitude in the construction of cars wherein the other portions are standard.

A steel car underframe of my improved construction is comparatively simple, comprises a minimum number of parts, all of 40 which can be made up from commercial rolled shapes and sheets and the various parts of the underframe are arranged so as to utilize to greatest advantage the strength 45 of the material in supporting the entire load of the car body or superstructure and its contents, and the various parts of the underframe are designed and arranged so as to effectually resist all service strains and buff- 50 ing shocks to which the underframe may be subjected.

It will be readily understood that minor changes in the size, form and construction of the various parts of my improved underframe can be made and substituted for those 55 herein shown and described without departing from the spirit of my invention, the

scope of which is set forth in the appended claims.

I claim:

1. In a metallic car underframe a pair of side sills, each comprising a plate extending continuously from one end of the car to the other, reinforcing members applied to the top and bottom edges of said plates, suitable transverse members connecting the side sills, a center sill, reinforcing members applied to the lower edge of the center sill plate and floor plates fixed at their inner edges to the upper portion of the center sill and having their outer edges overlapping the upper portions of the side sills and secured thereto. 60

2. In a metallic car underframe the combination with a web plate center sill and web plate side sills of floor sheets having their side edges flanged downwardly and attached to the upper portions of the center sill and side sills and reinforcing plates interposed between the upper portions of the web plate side sills and the downwardly 75 bent side edges of the floor sheets. 80

3. In a metallic car underframe the combination with a web plate center sill and web plate side sills of floor sheets having their side edges flanged downwardly and attached to the upper portions of the center sill and side sills and a cover plate applied to the inner edges of the floor sheets over the web plate center sill. 85

4. In a metallic car underframe the combination of a center sill, web plate side sills, longitudinally extending reinforcing members applied to the upper and lower portions of said side sills and floor sheets having their side edges flanged downwardly and 90 connected to the upper portions of the web plate center sill and side sills. 95

5. In a metallic car underframe in combination, a center sill, side sills comprising a pair of vertically disposed web plates provided with reinforcing members along their upper and lower edges, and floor plates attached to the center sill at their inner edges, and having their outer edges secured to the vertically disposed web plates of the side 100 sills and to the upper reinforcing member 105 thereon.

In testimony whereof I hereunto affix my signature in the presence of two witnesses, this 20th day of November, 1911.

VICTOR M. SUMMA.
